HAIRPIN CLASP

Frank Interrante, Brooklyn, N. Y.

Application February 14, 1935, Serial No. 6,449

3 Claims. (Cl. 132—50)

This invention relates to new and useful improvements in a clasp for sculpture hair curls formed by finger waving or the like.

The invention has for an object the construction of an article as mentioned which is characterized by a single piece of wire bent and formed to have a top arm consisting of two side members for engaging across the outer face of a curl, and also having a bottom arm for engaging across 10 the inner face of the curl.

More particularly, the invention proposes a novel construction of a sculpture hair curl clasp so that it may be readily applied in position and very efficiently hold the finger wave and the curls.

Still further it is proposed to construct the hair clasp so that it may be easily withdrawn from the finger wave when desired.

A further object of the invention is the teaching of various embodiments of the invention which 20 are adapted to utilize substantially the identical inventive principles.

Another object of the invention is the construction of a device as mentioned which is simple and durable and which can be manufactured at a reasonable cost.

For further comprehension of the invention, and of the objects and advantages thereof, reference will be had to the accompanying drawing and following description, and to the appended claims 30 in which the various novel features are more particularly set forth.

In the accompanying drawing forming a material part of this disclosure:

Fig. 1 is an elevational view of a curl, with a 35 hair clasp applied according to this invention.

Fig. 2 is a plan view of the hair clasp shown in Fig. 1.

Fig. 3 is a side elevational view of Fig. 2.

Fig. 4 is a perspective view of a hair clasp constructed according to a modification of the invention.

Fig. 5 is a plan view of Fig. 4.

Fig. 6 is a perspective view of another hair clasp constructed according to a still further modified form of the invention.

Fig. 7 is a plan view of Fig. 6.

Fig. 8 is a plan view of a hair clasp according to another embodiment of the invention.

Fig. 9 is a plan view of a hair clasp according 50 to another embodiment of the invention.

Fig. 10 is a side elevational view of Fig. 9.

Fig. 11 is a plan view of a hair clasp according to a still further modified form of the invention.

Fig. 12 is a plan view of a hair clasp according 55 to a still further modification of the invention.

Fig. 13 is a side view of Fig. 12.

Fig. 14 is a plan view of another modified form.

Fig. 15 is a side view of Fig. 14.

The hair clasp shown in Figs. 1—3, inclusive comprises a single piece of wire having a top arm 5 10 consisting of side members 10' and 10'' for engaging across the outer face of a sculpture curl 21 formed by finger waving or any other manner, and including a bottom arm 11 for engaging across the inner face of the curl. The bottom 10 arm 11 consists of two side members 11' and 11''. The front ends of the side members 10' and 10'', are connected with a bent section 12. This bent section is slightly extended upwards when viewed in side elevation (see Fig. 3) so that there is a 15 wedge action tending to separate the arms when the clasp is engaged upon the curl. The rear ends of the side members 10' and 10'' are connected with small bends 13 with the rear ends of the side members 11' and 11''. These bends 13 are sub- 20 substantially in vertical plane, except for the fact that the planes are at slight angles to the vertical so that in plan view the side arms 11' and 11'' are located slightly spaced outwards from the side 25 arms 10' and 10''.

The free ends 14 of the side arms 11' and 11'' are bent outwards within a common plane with the side arms. The front areas of the side arms 11' and 11'' are formed with wavy sections 15 arranged with the waves in a common plane with 30 the said side arms. Fig. 1 illustrates the clasp in engaged position holding a finger wave 21. It will readily be understood from a mere inspection of Fig. 1 that the clasp can readily be slipped off from the curl. The feature of the waved portions 35 15 being in the same plane as the side arms 11' and 11'', is that the operative holding effect of the clasp will be materially increased.

The advantage of having the side arms 11' and 11'' slightly spaced outwards from the side 40 arms 10' and 10'' resides in the fact that then the clasp will be capable of tending to slightly bend the hair curl and so obtain a tight grip to maintain its position and properly hold the wave in formation. The advantage of having 45 the ends 14 bent outwards resides in the fact that the possibility of accidentally injuring a person with a sharp edge will be materially reduced.

In Figs. 4 and 5 another embodiment of the 50 invention has been disclosed which is very similar to the preferred form and the identical parts may be recognized by the identical reference numerals. This form of the invention distinguishes from the prior form in the fact that the 55

rear ends of the arms 10' and 10'' are joined with the arms 11' and 11'', respectively.

The portions 13' preferably are inwardly bent portions and touch one another and close the gap 13''. With this arrangement the clasp will have an increased holding effect on the curls and prevent any hair strand from entering between the side arms 10' and 10''.

In Figs. 6 and 7, another embodiment of the invention has been disclosed which is very similar to the form shown in Figs. 1, 2, and 3, but distinguishes in very minor respects. The side arms 11' and 11'' are not formed with the wavy sections 16. Each of the side arms 11' and 11'' is formed with upward directed wave portions 16 adapted to engage inside of the side arms 10' and 10''. The side arms 11' and 11'' are normally disposed outside of the side arms 10' and 10'' as illustrated by the full lines in Fig. 7. When the clasp is engaged upon the hair, it is possible to manually press the side arms 11' and 11'' together so as to cause the upward directed portions 16 from the side arms 11' and 11'' to engage inside of the side arms 10' and 10'' to engage the clasp firmly upon the hair. The clasp cannot be removed unless the side arms 11' and 11'' are first released by forcing them outwards back to their original positions. In other respects this form is similar to the forms previously described and the same parts have identical reference numerals.

In Fig. 8 another form of the invention has been disclosed in which the hair clasp is formed with straight parallel bottom arms 11' and 11''. In another respect this form of the invention is identical with the form illustrated in Figs. 4 and 5.

In Figs. 9 and 10 another modified form of the invention has been disclosed in which the hair clasp is formed from a single piece of wire having a top arm 10^a and a bottom arm 11^a. The top arm 10^a is formed with side members 10' and 10''. A bend 12 connects the front ends of the side members 10' and 10''. At the rear ends 45 the side members 10' and 10'' are connected with downward bend 13 and then are connected by a twisted area 18. Only one of the side members continues from the twisted area 18, producing the bottom arm 11^a. This bottom arm is formed 50 with a central wavy area and terminates at the end in a straight portion. It is arranged between the side members 10' and 10''.

In Fig. 11 another modified form of the invention has been disclosed which is identical to the form shown in Figs. 9 and 10 except the top arm 10^b is formed with diverging side members 10' and 10'' and the bottom arm 11^b is formed with twists 18' throughout its length.

The form of the invention illustrated in Figs. 12 and 13 is similar to that disclosed in Fig. 8 except that the bottom arm 11 is formed with diverging sections 11' and 11''.

In Figs. 14 and 15 another modified form of the invention has been disclosed in which the clasp comprises a single piece of wire having a top arm 10 and a bottom arm 11. The top arm 10 is composed from side members 10' and 10'' connected together at one end by the bend 12 which is directed slightly upwards as previously described. The rear ends of the side members 10' and 10'' are connected by bends 13 with side members 11' and 11'' constituting the bottom 11. The side members 11' and 11'' are straight but diverge from their rear ends. They are located slightly outside of the side members 10' and 10''. 5 10

While I have illustrated and described the preferred embodiment of my invention it is to be understood that I do not limit myself to the precise construction herein disclosed and the right is reserved to all changes and modifications coming within the scope of the invention as defined in the appended claims. 15 20

Having thus described my invention, what I claim as new and desire to secure by United States Letters Patent is:

1. A hair curl clasp, comprising a single piece of wire having a top arm for engaging across the outer face of a curl, and a bottom arm for engaging across the inner face of the curl, each of said arms consisting of two side members, the front ends of the side members of the top arm being connected with a bent section, the rear ends of the side members of the top arm continuing into the rear ends of the side members of the bottom arm, the side members from the bottom arm being formed with upward bent portions adapted to engage the inner side of the side members of the top arm to latch the clasp closed on the hair. 30 35

2. A hair curl clasp, comprising a single piece of wire having a top arm for engaging across the outer face of a curl, and a bottom arm for engaging across the inner face of the curl, each of said arms consisting of two side members, the front ends of the side members of the top arm being connected with a bent section, the rear ends of the side members of the top arm continuing into the rear ends of the side members of the bottom arm, and connected with bent portions themselves bent together for closing the gap between the side members. 45 50

3. A hair curl clasp, comprising a single piece of wire having a top arm for engaging across the outer face of a curl, and a bottom arm for engaging across the inner face of the curl, each of said arms consisting of two side members, the front ends of the side members of the top arm being connected with a bent section, the rear ends of the side members of the top arm continuing into the rear ends of the side members of the bottom arm, the side members cocontacting at their rear ends. 55 60
